PROCESS FOR CLEANING GRANULAR
MATERIALS

Frank R. Ofner, Portland, Oreg., assignor to Industrial Powertronix, Inc., Portland, Oreg., a corporation of Oregon

Filed May 26, 1958, Ser. No. 737,866

3 Claims. (Cl. 209—2)

This invention relates to a process and apparatus for cleaning granular materials, and more particularly to such a process and apparatus for washing grains such as wheat.

Many granular materials must be cleaned as a step in the processing thereof, and this is especially true of grain. For example, it was early discovered that a number of advantages accrued from washing wheat prior to converting the same into flour. Among such advantages are the removal of smut and dirt, loosening of the outer beewings, an improvement in the general sanitary condition of the grain, and the production of a more uniform flour having a low ash content, improved color, better milling qualities and an increase in the patent flour produced. In view of these advantages, it is quite common today for millers to wash wheat before grinding the same into flour.

Essentially, a single type of washer is in use, and it comprises a large horizontally disposed cylinder. Wheat and water are fed to a closed section of the cylinder where the washing action takes place. A revolving spiral ribbon within the cylinder carries the wheat after washing through a perforated section thereof, wherein the wheat is rinsed. The rinsing action is accomplished and controlled through manual or mechanically operated valves that determine the quantity of water delivered to the cylinder. Thereafter, the spiral ribbon continues to advance the rinsed grain to a further section of the cylinder wherein a constant flow of air, actuated by the movement of the ribbon, removes portions of the surface moisture and, in conjunction with the centrifugal force developed which drives off additional water, partially dries the grain. In addition, a constant air flow is circulated through the grain and continues the drying action until the wheat is discharged.

Although it is common to wash grain and oftentimes essential because of the sanitation controls imposed by the Federal Food and Drug Administration, a number of disadvantages are attendant with the washing process. Such disadvantages include an excessive increase in the moisture content of the grain; the difficulty of obtaining an adequate water supply, which must comprehend three to five gallons of water per bushel of grain; the additional power cost of operating the washer apparatus; and the additional maintenance requirement cannot be overlooked as an economic factor. Other disadvantages which have existed heretofore but which have been overcome in the manner disclosed in my patents, Nos. 2,835,984 and 2,835,985, are the loss of grain carried off by the wash water, the disposal of the wastes, and the high water costs resulting from the inability to reuse the wash water.

Other negative aspects of the general cleaning process (water washing being one step thereof) are evidenced in the high initial cost of the equipment employed and the vast amount of space required, which may encompass several floors in a mill and incorporate as many as seventeen separate cleaning steps. Additionally, the washers are difficult to operate and, as a consequence, are often improperly used so that the grain is not adequately cleaned, and even worse acquires a gummy coating thereon.

In view of the desirability and frequent necessity of washing grain, an object of the present invention is to provide a process and apparatus for accomplishing the same which will overcome a number of the important disadvantages inherent in the prior art systems. Another ob-

2

ject of the invention is that of providing a process and apparatus for washing wheat, other grains and the like, which will optimize in a single washing stage the advantages now gained in multiple washing stages, and wherein the system is simple and compact with the result that it occupies an insignificant amount of space compared to the space requirement of prior systems (for example, a space of about 5' x 12' as opposed to several floors of equipment for washers having a capacity of about 330 bushels per hour).

Still another object is that of providing a system of the character described, wherein the apparatus because of its structural simplicity and the minimization of relatively moving components, requires but a small initial investment, has a low maintenance cost and has a low power demand. Moreover, the installation expenses are low and the equipment can be installed quite rapidly and, if desired, as an integral system.

Yet another object is in the provision of an improved washing process for wheat and the like and for apparatus to carry forth the same, that materially decreases the damage to the grain that is inherent in the scouring action provided by present washers, but which at the same time affords a much better and more thorough cleaning of the grain whereby the product yield is greater. A further object is to provide a washing and drying system (it may be noted that the term "washer" as used in the trade comprehends a drying stage, and consequently the concepts of washing and drying per se are not necessarily distinguished) of the character described, wherein a much better control of the moisture content of the end product is attained—so much better in fact that the control may be considered substantially absolute.

Yet a further object is in the provision of a system in which the wash water is used to its capacity whereby a much more thorough washing of the granular material is attained per unit of wash water, with the result that the over-all consumption of wash water is diminished. Additional objects and advantages of the invention will become apparent as the specification develops.

An embodiment of the invention is illustrated diagrammatically in the single view which comprises the drawing hereof.

The process and apparatus illustrated in the drawing comprise three stages that, for identification, may be designated as mixing, washing, and separating and drying. The drawing is provided with legends corresponding to this nomenclature and indicating the structural components comprising parts thereof.

The first stage comprises a mixer 10 of inverted, frustoconical configuration having a conduit 11 feeding into the hollow interior adjacent the upper end thereof, and which is adapted to supply liquid or wash water thereto. Also communicating with the interior of the mixer 10 is a conduit 12 through which granular material such as wheat or other grain is fed thereto. The conduit 12 may comprise a portion of a screw conveyor, and if so will have a feed screw 13 cooperatively arranged therewith. It will be noted that both of the conduits 11 and 12 have elongated openings that communicate with the mixer 10 along an arc of the surface thereof whereby the infeed of the materials, and particularly the wash water, results in a swirling motion thereof wherein the material tends to move through convolutions following the surface contour of the mixer. This results in a thorough and intimate mixing of the liquid and solids.

The lower end of the mixer 10 is provided with an outlet communicating with a pipe or conduit 14 that discharges into the casing 15 of a pump denoted in general with the numeral 16. The pump is preferably of a large volume, low head type; and in the form shown, has multiple stages indicated with the numerals 17, 18, and 19,

having respectively mounted therein impellers 20, 21 and 22. It will be apparent that the mixture of solid granules and wash water is fed into the pump stage 17, is then forced through the stages 18 and 19, and into an outlet pipe or conduit 23. The impellers are respectively mounted upon shafts 24, 25 and 26, rotatably driven by a motor 27 through a gear assembly 28. Ordinarily, the impeller 21 and its shaft 25 will be rotated reversely with respect to the impellers 20 and 22 and the shafts thereof.

Preferably, the interior surfaces of the pump casing 10 and the surfaces of the impellers therein will be coated with a resilient material such as rubber to minimize abrasion of the grain. The function of the pump is to further mix the liquid and solids, and to deliver the material to the conduit 23 with a sufficient pressurehead so that it rises upwardly through the vertically disposed washer 29.

The washer 29 constitutes a tank or cylinder having a plurality of paddles or agitators mounted therein for rotation, and which are driven by a motor 30 through appropriate gearing denoted with the numeral 31. In the form shown, there are five paddles 32 through 36 which are vertically oriented and extend substantially from top to bottom of the mixer tank 29. At the upper end of the washer 29 is an outlet communicating with a delivery conduit 37. It will be noted that the interconnection of the outlet and delivery conduit extends along a substantial portion of the surface of the tank, and defines a gradually enlarging opening. Essentially, the movement of the material within the tank at the upper end thereof will have a counter-clockwise direction, or from left to right; and thus, the opening incrementally enlarges toward the right which then facilitates the movement of material into the conduit 37. The washer 29 is provided with a sloping bottom wall equipped with a conduit 29a at the lowermost extremity thereof, through which heavy materials are removed from the washer, and with an outlet 29b at the upper end thereof through which foam, froth and lightweight particles are withdrawn from the washer.

The conduit discharges into a centrifuge 38 through a head or closure manifold 39 that remains stationary as the centrifuge is rotated, and is sealingly related thereto in order that there be no seepage of material therebetween. The centrifuge has an inverted, generally frustoconical configuration, and is equipped at the lower end thereof with an outlet 40 through which the liquid and any clays or other colloidal suspensions therein are discharged. Adjacent the upper enlarged end of the centrifuge is a draw-off manifold 41 communicating with the interior thereof, through which heavy waste materials are discharged as, for example, rocks (that is, materials having a greater weight than the grain kernels being washed). This latter material is drawn off through a manifold 42 communicating with the centrifuge 38 intermediate the ends thereof and at a location below that of the manifold 41. It is apparent that the manifolds 41 and 42 communicate with the centrifuge along the peripheral surface thereof, and that a sealing relation must be defined therebetween to prevent the loss of materials through such connections.

The manifold 42 discharges the wet wheat or other granular material toward the upper surface of a downwardly inclined screen 43, the lower end of which terminates above a conveyor 44. Heated air is blown upwardly through the screen 43 as indicated by the arrowed lines 45. Disposed above the screen 43 is a suction hood 46 adapted to be connected through a conduit 47 with a suction fan (not shown). The volume and velocity of the heated air indicated by the arrows 45 is sufficient to float the grain, which it is desired to recover, above the surface of the screen whereby this floating mass of grain flows downwardly and onto the conveyor 44 which carries it to storage containers where it is held pending further processing. Materials heavier than the grain will not be

5 supported by the air curtain, and will fall downwardly through the screen 43 and to an appropriate waste receiver therefor. Similarly, waste materials which are lighter in weight than the grain will be carried upwardly by the air stream and into the suction hood 46. Consequently, only the clean grain kernels will be delivered to the conveyor 41.

It will be evident that conventional air heaters (not shown) may be provided for supplying the heated air bank flowing upwardly through the screen 43; and since the heated air flows through the grain mass and intimately surrounds the grain kernels throughout the entire path of movement thereof across the length of the screen, an efficient drying of the grain is attained; and because 15 the drying effect is directly related to the temperature of the air, it may be regulated by appropriate selection of the temperature thereof. Therefore, an accurate control over the moisture content of the grain delivered to the conveyor 44 is provided.

It will be apparent that the functioning of the apparatus described comprises a cleaning process wherein granular materials such as wheat, other grains, etc., are first mixed with a liquid such as water to thoroughly encase the particles in the liquid. Thereafter, the resultant mixture 20 is agitated to effect a movement of the liquid over the surfaces of the solid particles to flush foreign materials therefrom. Certain of these foreign materials may be soluble in the liquid as, for example, smut removed by wash water from wheat kernels, and will thereafter remain in the liquid as a colloidal suspension. Other particles may not be soluble as, for example, small rocks or stones which are collected with the wheat, certain types of earth and dirt particles, etc. Though flushed from the 25 granular material, such foreign solids will remain in the liquid and will be randomly distributed therethrough along with the granules.

Next, the various solids in the water are stratified to separate the grain. Such stratification is accomplished in accordance with the weight, as by flotation in a centrifuge. 30 It will be appreciated that numerous forces coact on the various particles to effect the stratification. First, there is the centrifugal force, and in view of the configuration of the centrifuge, the heavier particles such as rocks and stones will accumulate near the upper end of the centrifuge since the mass of such particles will result in a greater centrifugal force thereon for a given velocity of the centrifuge. As is well known, various other factors in addition to centrifugal force act on solids contained within a liquid disposed in a centrifuge, and for convenience some of the more important of these factors will be mentioned. Thus, because the particles are contained in a liquid body, the inherent buoyancy if any of such particles will tend to make them rise within the centrifuge because of the liquid pressure exerting an upward force on the particles. The greater the specific gravity of each of the particles, the less effective will be the net effect of the upward liquid pressure tending to cause the same to rise because the existing downwardly acting gravitational forces will have a greater net effect on such heavier particles. 35 Also, the frictional force between certain of the particles and the surface of the centrifuge will have some incidental determination of the final position attained by the particles.

Considering all of these factors which are present in 40 any centrifuge and selecting the proper centrifuge in accordance therewith, a stratification of the solids is accomplished and the grain along with other particulate matter of generally similar mass will comprise a stratum, which is then withdrawn from the centrifuge. These 45 materials are again stratified in an air stream having a velocity such that particles heavier than the grain fall downwardly through the air stream and into a collection receptacle therefor. On the other hand, particles that are lighter than the grain are carried upwardly and are collected in the suction hood 46. The intermediate grain

stratum is floated through the air stream and is deposited on a conveyor. Thus, the separation of the grain from the foreign materials comprehends a flotation or stratification thereof, both in liquid and gaseous media.

The air is heated to a temperature such that the grain which accumulates moisture in the mixing, washing and liquid flotation procedures, is dried to whatever moisture content is required. Ordinarily, the moisture content desired varies from about 10% to 20% depending upon the particular mill. To remove a greater amount of moisture from the grain, it is only necessary to elevate the temperature of the air stream, and such control over the air temperature is an easy procedure of considerable accuracy and may be determined manually or automatically. Consequently, the moisture content of the grain may be accurately controlled by means of this drying procedure.

In certain areas and in some installations, it may be feasible to eliminate the mixer 10 and pump 16; and in such event the wash water and wheat may be introduced directly into the washer 29. Such a condition is illustrated in the drawing by the conduits 11' and 12'. The water will be fed into the washer through the conduit 11', and wheat solids through the conduit 12', and consequently a screw conveyor 13' is illustrated in conjunction with the latter conduit. A direct introduction of the materials in the washer 29 is particularly suitable with the liquid stratification apparatus shown by broken lines at the right side of the drawing.

Such stratification apparatus can be used alternatively with the centrifuge 38 which, as has been brought out before, is simply a liquid stratification device. Thus, it may be used with the direct introduction of the water and grain into the washer, or with the prior described arrangement wherein the water and wheat solids are first mixed in the device 10, and are further mixed and agitated in the pump 16.

Where this apparatus is employed, the wheat and wash water will be removed from the washer 29 through the conduit 37' which empties into the stratification container 38'. The admixture of wheat and wash water is preferably fed into the container 38' adjacent the upper end thereof, and it will be noted that this container is provided with a draw-off pipe or outlet conduit 40' at its upper end, and with a screw conveyor 42' connecting therewith at its lower end. An air inlet 48 is connected to the inclined bottom wall of the tank or container 38', and has a screen 49 extending thereover. The screen will be a fine mesh member having countless tiny apertures that permit air and liquid to move therethrough, but which will prevent grain and particles of similar size from passing through it.

While the grain and water admixture is fed into the upper end portion of the tank, air is blown thereto through the infeed conduit 48. The air stream is broken up by the fine mesh of the screen 49, and moves upwardly through the tank as a mass or blanket of bubbles. Such bubbles entrap the materials that are lighter than the grain particles, such as chaff, straw, dust, etc., and carries the same upwardly to the conduit 40' which removes this material from the tank. The heavier grain and any other heavier particles move downwardly through the tank 38', and the grain is withdrawn therefrom by means of the screw conveyor 42'. Particles and other matter which are heavier than the grain will descend to the lowermost portion of the tank 38', and may be withdrawn therefrom through a suitable outlet.

The conveyor 42' leads to the air stratification apparatus heretofore described, and terminates at the same location as that of the conduit 42. Thus, the grain is dried by the heated air 45 and is further separated from both lighter and heavier particles as set forth hereinbefore, and is then deposited on the conveyor 44.

It has been found that the washing procedure may be facilitated by mixing a chemical additive with the wheat and wash water admixture. The function of such chemical additive is to assist in the separation of the grain from the unwanted materials in the liquid separation or stratification step. More specifically, the additive serves to increase the rate of precipitation and flotation. Consequently, an additive may be used which serves as a wetting agent to cut the film of grease off of the wheat particles—that is, it reduces the surface tension of the water, thereby permitting the grain particles to become wet so that the buoyancy thereof is decreased and they sink or descend through the liquid body much more rapidly. Also, the light weight particles which are removed from the grain are encapsulated in a film provided by the additive, and are carried upwardly through the water at a more rapid rate. An example of such additive is pine oil.

Desirably, the chemical additive is employed with the liquid separation apparatus 38' for the rising air bubbles are encased in an oil film surface, and thereby trap the dirt and unwanted particles and more readily carry the same to the upper end of the tank for discharge therefrom through the conduit 40'. The additive may be introduced into the wheat and water admixture at various locations in advance of the liquid separation or stratification equipment, as for example, just prior to the infeed of the mixture into the washer 29 as shown in the drawing.

While in the foregoing specification an embodiment of the invention has been set forth in considerable detail for purposes of presenting an adequate disclosure thereof, it will be apparent to those skilled in the art that numerous changes may be made in such details without departing from the principles and spirit of the invention.

35 I claim:

1. In a process for cleaning wheat and the like, the steps of mixing the wheat with water, agitating the resultant mixture in a washer to flush foreign materials from the wheat, isolating the wheat by flotation and stratification from both lighter weight and heavier weight solids in the mixture in accordance with the relative weights thereof, and withdrawing the wheat thus isolated from the washer.
2. The process of claim 1 in which the further step is included of isolating the withdrawn wheat from other of the solids withdrawn therewith by introducing the withdrawn material into a container and by passing air bubbles upwardly therethrough to effect an upward movement of the lighter weight solids while those of heavier weight precipitate downwardly through the bubbles.
3. The process of claim 2 in which the step is included of introducing a wetting agent into the mixture prior to the aforesaid step of passing air bubbles therethrough.
